Des. 189,068
Patented Oct. 18, 1960

189,068

POURING SPOUT

Robert Phillips, New York, N.Y. (67-87 Booth St.,
Forest Hills, N.Y.), and Bernard B. Levine, 530 E. 90th
St., New York, N.Y.

Filed Feb. 1, 1960, Ser. No. 59,220

Term of patent 14 years

(Cl. D58—26)

Fig. 2

Fig. 1

Fig. 3

Fig. 4

Fig. 5

Fig. 6

Figure 1 is a front elevational view of a pouring spout embodying our new design;

Figure 2 is a side elevational view thereof;

Figure 3 is an elevational view taken approximately 45° from the right of Fig. 1;

Figure 4 is a top plan view thereof;

Figure 5 is a bottom plan view thereof; and

Figure 6 is a rear elevational view thereof.

We claim:

The ornamental design for a pouring spout, as shown.
